(No Model.)

L. F. JOHNSTON.
HOUSE CLEANING IMPLEMENT.

No. 293,034.

Patented Feb. 5, 1884.

Attest;

G. Haeter Fowler

E. Johnson

Inventor,

Larkin F. Johnston

Larkin F. Johnston

Atty.

UNITED STATES PATENT OFFICE

LARKIN F. JOHNSTON, OF SPRINGDALE, ARKANSAS.

HOUSE-CLEANING IMPLEMENT.

SPECIFICATION forming part of Letters Patent No. 298,084, dated February 5, 1884.

Application filed August 9, 1883. (No model.)

To all whom it may concern:

Be it known that I, LARKIN F. JOHNSTON, a citizen of the United States of America, residing at Springdale, in the county of Washington and State of Arkansas, have invented certain new and useful Improvements in House-Cleaning Implements; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention is a new and useful improvement in mop and brush holders, and has relation to means for washing and scouring floors, walls, and ceilings, and cleaning carpets and other articles; and it consists in the novel construction and arrangement of a pair of oblique grasping-jaws pivoted together, which are designed to grasp and hold between their extremities the mop or brush for sweeping, and as readily release and drop said articles, the handles of said jaws being provided with a ratchet and connection, whereby they are held together or unclosed, as will be hereinafter shown and described.

20 In the accompanying drawings, Figure 1 is a side view of my improved cleaning and scrubbing device. Fig. 2 is a sectional view taken on the line $x-x$ of Fig. 3, and Fig 3 is a rear view.

25 In the aforesaid accompanying drawings, the letter A designates the curved main arm of the tongs, which extends obliquely from its tang or coupling end a to its jaw b . This arm is designed to be connected to a broom-handle, or to a handle, B, having attached to

30 it a ratchet-bar, d.

C indicates the movable arm of the implement, also curved and pivoted to the main arm at c . This arm is provided at its handle end with a connection, e, which has a spring or elastic portion, f, whereby it is adapted to grasp articles of varying thicknesses, which the teeth of the ratchet, to which the other end e of the connection is attached, will not otherwise accommodate. This connection

35 may be made of wire of suitable size. One

end of the handle is provided with a socket or attachment, h , for the tang of the main arm, and if short its other end may be arranged for coupling with another handle - section. The arms being oblique, the article which is placed between them, whether it be a mop, cloth, sponge, or sweeping-brush, F, is held in an oblique position suitable to working overhead and on walls and floors. The casting attached to the brush F is provided with a longitudinal rib, l , on its back, provided with horizontal flanges, m of proper shape, the said rib l being adapted to be grasped by the jaws of the arms. The rubber r serves to mass or collect water and suds in mopping or sponging floors.

40 From the foregoing description it will be apparent that the tongs can be readily manipulated through the agency of the ratchet and yielding connection to grasp the rib of the brush, and can be as readily operated to unclasp and release the said brush and grasp a sponge, mop, or cloth. Moreover, the yielding spring connection permits the side play of the pivoted jaw in the event of any lateral strain or shock being received by the brush or mop.

45 I am aware that prior to my invention mop-holders have been provided with pivoted arms or jaws which were provided with means for retaining the arms or jaws rigidly closed upon the mop, and I do not claim such as my invention.

50 Having thus described my invention, what I claim as new, and desire to secure by Letters Patent, is—

55 1. A pair of tongs arranged obliquely to the handle, and adapted to grasp and retain between them a brush, mop, or other article for cleaning purposes, one of said tongs being connected to the handle, and the other being movable and pivoted to the fixed tong, and a spring-connection secured to the end of said pivoted tong, and adapted to engage a ratchet on the handle, substantially as and for the purpose set forth.

60 2. The improved brush and mop holder, consisting of the arms A, C, pivoted to each other, and provided with jaws, as shown, one of the arms being secured to a handle, and the other

having a perforated end and a spring connecting means adjustably secured to the handle, the parts being combined and organized substantially as shown, and for the purpose set forth.

3. In a house-cleaning implement, a brush having a longitudinal flanged rib on its rear side, and a rubber, *r*, at or near its edge, substantially as set forth.

In testimony whereof I affix my signature in presence of two witnesses.

LARKIN F. JOHNSTON.
